PILE DRIVING CAP

James M. Dolan, Elizabethtown, N. C.

Application April 27, 1936, Serial No. 76,687

2 Claims. (Cl. 61—77)

The present invention appertains to new and useful improvements in equipment and structure for the purpose of driving pilings by explosives.

The principal object of the present invention is to provide a means for capping piling in such a manner that when the driving charge is exploding, the cap will not become displaced from the top of the piling on which it is located.

Other important objects and advantages of the invention will become apparent to the reader of the following specification.

In the drawing:—

Figure 1 represents a vertical sectional view through the cap applied to a piling.

Figure 2 is a top plan view of the cap structure.

Figure 3 is a top plan view of one of the clamp members and its bolts in separated relation.

Figure 4 is a top plan view of the cap without the clamp members.

Referring to the drawing wherein like numerals designate like parts, it can be seen that numeral 5 represents a piling while numeral 6 represents a cylindrical-shaped cap closed at its upper end as at 7 and provided with an outwardly disposed flange 8 at its lower open end.

A pair of clamp structures 9—10 are employed for retaining the cap in position. Each clamp consists of a pair of semi-circular shaped members 11—11 having outwardly disposed ears 12 at their ends and these ears are apertured to receive the bolts 13 on which nuts 14 are placed.

It can be seen that the upper clamp 9 is positioned around the cap 6 and bears against the flange 8 while the lower clamp 10 binds directly against the piling 5.

To connect these clamp structures, a pair of

connecting rods 15—15 are employed, each being provided with an eye at each end thereof denoted by a numeral 16 through which the aforementioned bolts 13 are disposed.

While the foregoing specification sets forth the invention in specific terms, it is to be understood that numerous changes in the shape, size, and materials may be resorted to without departing from the spirit and scope of the invention as claimed hereinafter.

Having described the invention what is claimed as new is:—

1. A cap for piling comprising an inverted cup-shaped member provided with a laterally extending flange at its lower portion, a pair of clamp members, one of said clamp members being adapted to clamp against the piling, the other clamp member being adapted to clamp around the cup-shaped member and on top of said flange, and tie members between the said clamp members.

2. A cap for piling comprising an inverted cup-shaped member provided with a laterally extending flange at its lower portion, a pair of clamp members, one of said clamp members being adapted to clamp against the piling, the other clamp member being adapted to clamp around the cup-shaped member and on top of said flange, and tie members between the said clamp members, each of the said clamp members consisting of a pair of semi-circular shaped members folded together, said tie members consisting of rods provided with eyes at their opposite ends through which the bolts of the clamps are disposed.

JAMES M. DOLAN.
